UNITED STATES PATENT OFFICE

140,919

DESIGN FOR AN AIRPLANE

Harry A. Sutton, San Diego, Calif., assignor to
Consolidated Vultee Aircraft Corporation, San
Diego, Calif., a corporation of Delaware

Application June 19, 1944, Serial No. 114,099

Term of patent 14 years

(Cl. D71—1)

To all whom it may concern:

Be it known that I, Harry A. Sutton, a citizen of the United States, residing at San Diego, in the county of San Diego and the State of California, have invented a new, original, and ornamental Design for an Airplane, of which the following is a specification, reference being had to the accompanying drawings, forming a part thereof.

If the drawings:

Figure 1 is a top perspective view of an airplane, showing my new design;

Figure 2 is a top plan view;

Figure 3 is a front elevational view; and

Figure 4 is a side elevational view.

I claim:

The ornamental design for an airplane, substantially as shown.

HARRY A. SUTTON.
